(57) **CLAIM**

The ornamental design for audio/video cabling enclosure, as shown and described.

DESCRIPTION

FIG. 1 is a front perspective view of an audio/video cabling enclosure embodying my new design;
FIG. 2 is a back perspective thereof;
FIG. 3 is back perspective view thereof;
FIG. 4 is a front view thereof;
FIG. 5 is a back view thereof;
FIG. 6 is a side view thereof;
FIG. 7 is a side view thereof;
FIG. 8 is an end view thereof; and,
FIG. 9 is an end view thereof.
The broken line showing is included for the purpose of illustrating and forms no part of the claimed design.
